ATTORNEY.

UNITED STATES PATENT OFFICE

GEORGE D. SPACKMAN, OF COATESVILLE, PENNSYLVANIA, ASSIGNOR TO LUKENS STEEL COMPANY, OF COATESVILLE, PENNSYLVANIA, A CORPORATION OF PENNSYLVANIA

FORMER FOR SPINNING MACHINES

Application filed April 19, 1928. Serial No. 271,189.

The present invention relates to formers for use with spinning machines producing heads for pressure vessels. Heads for pressure vessels are provided with flanges and it was customary to employ a small radius in turning the flanges so that spinning plants are equipped with a great number of expensive mushroom heads or formers of various sizes but of short radius or practically no greater radius than is required for turning the flanges. There is a demand for pressure vessel heads of the so-called basket or elliptical types which require for their spinning formers of long radius.

The principal object of the present invention is to meet that demand for long radius vessel heads of various types without discarding the present equipment of mushroom heads or formers of short radius, and to provide for the use of these short radius mushroom heads along with elements which provide for making vessel heads of long radius and which are much less expensive than would be wholly new formers of long radius.

To this and other ends the invention generally stated may be said to comprise formers for spinning pressure vessel heads of different styles or types including so-called long radius, basket or elliptical heads, including interchangeable mushroom heads of short radius, and rings adapted in different combinations to provide different working contours including those of long radius, said rings and heads having means for causing them to rotate in unison and with the master head of a spinning machine.

The invention also comprises the improvements to be presently described and finally claimed.

In the following description reference will be made to the accompanying drawing forming part hereof and in which

Figure 1 is a view principally in central section illustrating a mushroom head of short radius showing also the pressure vessel head spun by its employment.

Fig. 2 is a similar view illustrating substantially the same mushroom head of short radius shown in Fig. 1 in association or combination with a ring which with the mush-

room head provides a former of long radius adapted for use in the production of a basket pressure vessel head.

Fig. 3 is a view similar to one-half of Fig. 2 and drawn to an enlarged scale and illustrating a former of the type there shown adapted for the production of a pressure vessel head of elliptical type.

In the drawing 1 is a mushroom head of short radius indicated by the arrow 2. 3 is a master head and between the master head 3 and mushroom head 1 there are means 4 for causing the parts to rotate in unison. The means indicated are a squared projection on the master head 3 and a squared socket in the mushroom head 1. Evidently the former described in cooperation with other parts of a spinning machines, not shown or described because too well understood, is adapted to spin a pressure vessel head 5 of short radius. In Fig. 2 there is shown interposed between the master head 3 and the mushroom head 1 a ring or body 6 adapted to rotate in unison with the master head 3 and the mushroom head 1. For this purpose a squared projection and socket 7 is provided.

The contour of the ring 6 provides a long radius as indicated by the arrow 8, and in connection with the contour of the mushroom head 1, there is spun a pressure vessel head 9 of the basket type.

The construction and mode of operation of the modification illustrated in Fig. 3 are as above described except that the ring or body 10 is lightened by the provision of cavities 11 and externally its conformation provides in association with the contour of the mushroom head 1 not only a long radius, as indicated at 12, but a contour adapted to produce a substantially elliptical type of pressure vessel head 12, as will appear by reference to the dash and dot lines. In each figure 13 indicates a flange of the pressure vessel head.

From the foregoing description it is evident that a plant equipped with mushroom heads 1 of short radius and of different sizes can, by the provision of rings or bodies, substantially like 6 and 10 and of different sizes which are not expensive, produce by proper combination of such rings and mush-

room heads formers not only of short but also of long radius and adapted for the production of pressure vessel heads of various types of which three have been referred to.

5 It will be obvious to those skilled in the art to which the invention relates that modifications may be made in details of construction and arrangement and matters of mere form without departing from the spirit of
10 the invention which is not limited to such matters or otherwise than the prior art and the appended claim may require.

I claim:

15 Formers for spinning pressure vessel heads of different styles including so-called long radius heads, comprising interchangeable mushroom heads of short radius and rings of long radius adapted in different combinations to provide working contours
20 of different radii, said rings and said heads having means for causing them to rotate in unison with each other and with a master head.

G. D. SPACKMAN.
